UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

APPARATUS FOR DRYING MATRICES.

1,211,994.

Specification of Letters Patent.

Patented Jan. 9, 1917.

Application filed February 23, 1911. Serial No. 610,234.

To all whom it may concern:

Be it known that I, HENRY A. WISE Wood, a citizen of the United States, residing at New York, in the county of New York and State of New York, have invented a new and useful Apparatus for Drying Matrices, of which the following is a specification.

This invention relates to the drying of stereotype matrices.

10 The principal objects of the invention are to provide for drying such matrices in a continuous uninterrupted operation by the employment of exceedingly simple mechanism so as to make the operation short and 15 exact, thereby uniformly drying the matrices and saving much space and time in the operation; to provide an exceedingly simple means whereby the necessary pressure can be applied to the drying blankets in a 20 uniform manner throughout the drying operation, so arranged preferably that although the pressure is substantially uniform throughout the extent of the matrix, it will very gradually increase during the drying 25 operation; and to provide means whereby the friction between the blankets and the pressing means can be reduced so as to prevent the creeping of the blankets and matrix.

30 The invention also involves improvements in the manner of mounting the blankets on the form.

Further objects and advantages of the invention will appear hereinafter.

35 Reference is to be had to the accompanying drawings, in which—

Figure 1 is a side elevation of a machine embodying one form of this invention; Fig. 2 is a fragmentary plan on enlarged scale of one of the forms with its drying blankets thereon; Fig. 3 is a side view of the same; Fig. 4 is a similar side view showing a modification; Fig. 5 is a view similar to Fig. 1 showing a modification thereof; Fig. 6 is a 40 sectional view on the line 6—6 of Fig. 5. Fig. 7 is a side view of a form, blanket, etc., used with the form of the invention shown in Fig. 5. Fig. 8 is an end view thereof. Fig. 9 is a side view similar to Fig. 5 showing another modification. Fig. 10 is a 45 sectional view of the same on the line 10—10 of Fig. 9, and Fig. 11 is a vertical longitudinal sectional view on enlarged scale of a form and accompanying parts suitable to be

used with the form of the machine shown in 55 Figs. 9 and 10.

Referring first to the first four figures, the invention is shown as embodied in a form in which the matrix heating device proper comprises a stationary steam table 10. This 60 steam table has a plane surface on the top on which the forms 11 are adapted to rest and along which they can be moved by hand or power. In the present instance each form is shown as having a pin 12 on each side 65 and two endless chains 13 are provided having projections 14 at intervals for engaging the pins and moving the forms along the table. The endless chains are shown as driven by a motor 15, shaft 16, worm 17, 70 and worm-wheel 18 on a shaft 19 on which two of the sprocket wheels 20 are located. The details of the driving mechanism are not shown herein. Any desired kind of mechanism can be employed for driving the 75 chains either continuously or intermittently, as desired. In this form of the invention, the heating table is shown as provided with brackets 23 on which is located a pressure shoe 24. This shoe preferably extends substantially throughout the width of the heating table and over its entire length, except 80 a space at one end on which the forms can be placed before they are introduced under the shoe and a space at the other end where the forms are left automatically by the operation of the chains and from which they can be removed by hand or power, as desired. The shoe is shown as having beveled 85 ends 25 for facilitating the entrance and discharge of the forms. Preferably it is finished on its lower side to reduce the friction so that the tendency of the blankets and matrix to creep will be partly or wholly overcome.

95 Each of the forms is shown as provided with a pair of outwardly and downwardly extending projections 28 at its forward end. The drying blankets 29 which rest on the matrix 30 are shown as doubled or folded 100 over a transverse rod 31 at the front end of the form. In Figs. 2 and 3 the blankets pass between the projections 28 and the rod is located up under them so that when pulled back tight, the parts are held securely in this 105 position. In the form shown in Fig. 4, the same conditions prevail except that the rod 31 does not engage the single continuous

projection 32 and the blankets pass around the projection instead of passing between two of them. In this form the rod 31 is held up by removable pins 33. In Fig. 3 a 5 smooth copper sheet 34 is employed over the blankets, but it can be of any other smooth surface material, that will not stretch, so as to prevent the creeping of the blankets and matrix and reduce the friction. This sheet 10 is a movable member moving along at the same rate as the form. The space between the surface of the table and the adjacent finished surface of the shoe is a little less than the type-high of the form, plus the height of the 15 package of drying blankets and the copper sheet 34 when that is used.

In the use of the device the forms are placed at one end of the table as they are received ready for drying. The blankets can 20 be laid on the forms by hand before or after they are placed on the table. The endless chain being started, the hooks 14 thereon will engage the pins 12 and move the forms along under the shoe 24. As the forms progress under the shoe, they are thoroughly heated from below and the moisture is driven 25 from the matrices into the blankets which are under pressure on account of the position of the shoe 24. In this case the shoe is shown as slightly inclined from the receiving 30 end to the discharge end. It is to be observed that the pressure exerted on the blankets and matrix will be substantially uniform throughout the heating operation 35 in the forms shown in Figs. 5 and 9 but if the shoe is inclined, as shown in Fig. 1, it will increase slightly but uniformly during the operation. The chains leave the forms on the other end of the table from which 40 they can be removed at will.

In the form shown in Figs. 5, 6, 7 and 8, the parts 10, 12, 13, and 14 are the same and the chains are operated in the same way. In this case, however, a second pair of chains 45 35 are employed driven in any desired way, and having thereon pressure plates 36. The two chains are spaced and driven so that the pressure plates will be advanced with the forms as they are moved forward by the 50 projections 14. The blankets are attached to the pressure plates by means of clamps 37 shown in Figs. 7 and 8. These clamps are operated by means of an eccentric shaft 38 and an operating arm 39 thereon. This 55 shaft has holes 44 for the reception of the end of a rod for turning the shaft. In this case another modification is shown in that the pressure is obtained by means of a fixed bar 40 having a spring-pressed shoe 41 thereon, in contact with the pressure plates as they are moved along. The compression 60 of the springs 42 tends to press the blankets into the matrix. The shoe 41 is held in place by headed studs 43 which connect it with 65 the stationary bar 40 and prevent its fall-

ing too low to engage the tops of the pressure plates as they are moved around. These traveling pressure plates also prevent the matrix and blankets from creeping.

In the form shown in Figs. 9, 10 and 11, 70 similar conditions prevail as in Fig. 1, but in this case the creeping of the blankets and matrix is prevented and the friction reduced by the use of an endless belt 45 which runs between the fixed shoe 46 and the pressure plates 47 which are located above the matrices. These pressure plates are supported by springs 48 from plates 49 that rest directly on the blankets. They are held in position and their upward motion limited 80 by headed studs 50.

It will be seen that in all the forms shown the matrices can be dried quickly and uniformly under either a perfectly uniform or uniformly increasing pressure the latter being 85 shown in Fig. 1 and that the devices for reducing friction while not absolutely necessary add greatly to the efficiency of the device.

While I have illustrated and described 90 several forms in which the invention can be embodied, I am aware that the drawings do not exhaust all the ways in which the invention can be carried out and therefore, I do not wish to be limited to all the details of 95 construction herein shown and described, but

What I do claim is:—

1. In a matrix drying device, the combination with a stationary heating table having 100 a top surface, and a form and matrix movable along said surface, of means spaced from said surface for constantly holding the form in contact with the heating table under pressure while the form is moved 105 along the table whereby the matrix will be dried during its motion by the heat from said table.

2. In a matrix drying device, the combination with a heating table having an upper 110 surface adapted to support a form with a matrix thereon in such a way that the form can be moved along the surface of the table in contact therewith and be heated thereby during its motion along the surface thereof, 115 of means supported by said table and located above it for exerting continuous pressure on the form while it is moving along the table.

3. In a matrix drying device, the combination with a heating table having an upper surface adapted to support a form with a matrix and blanket thereon in such a way that the form can be moved along the table and be heated thereby during its motion along 120 the surface thereof, of a shoe supported by the table and located above it for exerting continuous pressure on the blanket and form while moving along the table.

4. In a matrix drying device, the combi- 13

nation with a heating table having a surface along which a form with matrix and drying blankets thereon can be moved so as to dry the matrix during its motion along the 5 table, and a shoe supported by said table and located at a distance from said surface sufficient to permit the form with the matrix and blankets to pass between the surface and shoe, whereby the moisture from 10 the matrix will be driven into the blankets while they are under pressure by the heat from said table.

5. In a matrix drying device, the combination with a heating table having a plane 15 surface along which the forms are adapted to pass with the matrices and drying blankets thereon, of a shoe extending substantially the whole width of said surface and at a distance therefrom less than the normal 20 thickness of a form, matrix and blankets, so that when the form passes along between said surface and the shoe the blankets and matrix will be under a continuous pressure.

6. In a matrix drying device, the combination with a heating table having a surface 25 for receiving the forms and matrices to be dried, of a stationary shoe having a finished surface located adjacent to said surface in position to apply pressure to the blankets 30 on the forms while on the surface.

7. In a device for drying matrices, the combination of a heating table having a surface for receiving the forms, and a shoe located adjacent to said surface and substantially parallel therewith but slightly nearer 35 said surface at one end than at the other.

8. In a device for drying matrices, the combination of a heating table having a plane surface for receiving the forms, and 40 a shoe located adjacent to said surface and substantially parallel therewith but slightly nearer said surface at one end than at the other, and means for positively moving forms along said surface under the shoe toward 45 said nearer end thereof.

9. In a device for drying matrices, the combination of a heating table having a

plane surface for receiving the forms, and a shoe located adjacent to said surface having a finished surface on the side toward the 50 table, and having its receiving and discharging edges beveled off.

10. In a device for drying matrices, the combination of a heating table having a plane surface for receiving the forms, a shoe 55 located adjacent to said surface and substantially parallel therewith, and a smooth surfaced plate adapted to rest on the blankets for receiving the pressure from said shoe. 60

11. In a device for drying matrices, the combination of a heating table having a plane surface for receiving the forms, a shoe located adjacent to said surface and substantially parallel therewith, and means for 65 reducing the friction between the parts to prevent the creeping of the blankets and matrix.

12. In a device of the character described, the combination with a form having outwardly and downwardly extending projections at the end thereof, of a doubled drying blanket adapted to rest on said form and project down at the end thereof at which said projections are located, and a rod extending under said projections and surrounded by said 70 blanket where it is doubled. 75

13. In a device of the character described, the combination with a form having outwardly and downwardly extending projections at the end thereof, of a drying blanket 80 adapted to rest on said form and project down at the end thereof, at which said projections are located, a rod extending under said projections and surrounded by said 85 blanket, and a metal sheet located on said blanket.

In testimony whereof I have hereunto set my hand, in the presence of two subscribing witnesses.
